RATCHET SKI BINDER

William N. Bennett, Winter Haven, Fla., assignor to
Cypress Garden Skis, Inc., Cypress Gardens, Fla.
Filed Nov. 22, 1961, Ser. No. 154,123
7 Claims. (Cl. 9—310)

This invention relates to recreation and sporting activities and more particularly to an improved binder especially adapted for water skis.

Water skis are frequently used for short periods of time and by various skiers. Hence it is desirable that the bindings be easy to apply and remove.

Adjustable ski binders proposed heretofore have often times been difficult to operate or had parts protruding outside of the side edges of the ski. Among the difficulties accompanying some previous ski harnesses is the tendency to bind during adjustment, thus necessitating that two hands be used to operate the same in order to obviate or overcome such binding.

Accordingly it is the object of the present invention to provide an improved ski harness which is easy to operate and has a positive locking adjustment.

A further object is to provide a ski binding which is easily operable by one hand and which does not tend to bind against movement and hence make adjustment difficult.

A further object is to provide a relatively simple easily adjustable ski binding which is easy to operate both during adjustment to the foot and removal of the latter therefrom.

These and other objects of the invention will become apparent from the following description in conjunction with the accompanying drawing in which—

FIG. 1 is a fragmentary plan view of a ski binder constructed in accordance with the present invention;

FIG. 2, a side elevation of the structure of FIG. 1;

FIG. 3, a section on the line 3—3 of FIG. 5;

FIG. 4, a section on the line 4—4 of FIG. 5; and

FIG. 5, a plan view similar to FIG. 1 and illustrating the ratchet in engaged position.

Briefly stated, the ski binder of the present invention includes a heel piece positioned to reciprocate in longitudinal facing guideways at each side of the ski, one of the guideways having a ratchet, a bellcrank panel pivotally mounted on the heel piece and having its finger engageable part positioned along the longitudinal center line of the ski, and a fixed member adjacent thereto and behind the heel piece, depression of the lever releasing the ratchet and permitting movement of the heel piece by force applied along the centerline and in the appropriate direction.

With further reference to the drawing there is illustrated a ski 10 having a fixed toe plate 11 to which a toe cover 12 is attached. Behind the toe plate a pair of guides or slideways 14, 15 are attached to the sides of ski by fasteners 16. Slideway 14 has upper and lower strips 17, 18 connected by a web 19 which preferably is provided with slots 20 to permit the discharge of foreign matter therefrom such as sand. Guideway 15 has upper and lower strips 21, 22 connected by web 23 having slots 24. The rearward portion of the upper guide 21 of the slide way 15 is notched to form ratchet teeth 25, the teeth having transverse leading edges 26 and inclined trailing edges 27.

A heel plate 30 has its side edges received in the slideways between the upper and lower strips or guides, the lower surface of the heel plate being spaced above the surface of the ski as a result of being supported on the lower guides 18, 22, thereby preventing direct contact

2

between the heel plate and the ski obviating the possibility of binding action therebetween.

Mounted on the heel plate is a flexible heel cover 31. At one side of the heel cover 31 and adjacent to the edge 5 of the heel plate a bell crank lever 34 is pivotally mounted on a pin 35 secured in the heel plate. The lever has thumb or forefinger receiving end portion 37 and a panel tooth or dog 38 at its other end. In order to urge the dog 38 into engagement with the ratchet 25 a spring 39 is positioned around pin 35 and has one end 40 secured to the base 30 by means of an anchor hole 41 on the side adjacent to the finger portions 37 and its other end 42 abutting a stop 43 adjacent to the dog 38.

An abutment 45 projects upwardly from the heel plate 15 directly on the center line of the heel cover 31. The lever 34 is so constructed and arranged that the finger portion 37 is positioned adjacent to the abutment 45. Hence, to move the heel plate rearwardly, a skier operates the lever 34 by engaging the finger piece 37 and abutment 45, thereby releasing the ratchet, and applies rearward force to the abutment (along the longitudinal center line) thereby avoiding any angular application of force which would tend to cock the heel plate in the slideway and producing binding therein.

25 The dog 38 has its leading edge 38' inclined to engage with the inclined trailing edge 27 of the ratchet teeth 25 and has its trailing edge 38'' transversely disposed to engage the leading edge 26 of the ratchet teeth.

In the use of the device a skier moves the heel plate 30 rearwardly, if necessary, to permit easy insertion of a foot, this being accomplished by depressing the lever 34 and applying rearward force to the abutment 45 of the ski. After insertion of his foot, the skier may, by continuing depression of the lever 34, rapidly move the heel

35 plate forwardly into approximate position without the dog being engaged with the ratchet teeth. Then with the lever released, the skier may push forwardly on any portion of the heel piece, the angular inclination of the engaging surfaces of the ratchet and dog teeth permitting forward ratchet movement of the heel plate.

40 Accordingly it will be understood that the invention includes a ski binder, with spaced slideways receiving a heel plate, one of the slideways having a rack engageable by a panel having an operator engageable portion positioned substantially along the center line of the ski and an abutment directly behind the center of the heel cover to facilitate one hand adjustment of the heel plate without binding in the slideways.

45 It will be obvious to one skilled in the art that various changes may be made in the invention without departing from the spirit and scope thereof and therefore the invention is not limited by that which is illustrated in the drawings and described in the specification, but only as indicated in the accompanying claims.

50 What is claimed is:

1. A ski binder comprising
a toe plate rigidly attached to a ski,
a toe cover on the toe plate,
and an adjustable heel plate assembly spaced behind
the toe plate,

60 said assembly comprising spaced guideways at
each side of the ski,

said guideways comprising upper and lower
spaced guides connected by outer webs and
providing inwardly directed opposed channels,

70 the webs having openings to permit the
discharge of foreign material,
one of the upper guides having teeth formed
therein to provide a rack,

the leading edge of said teeth being transverse to said rack and the trailing edge of said teeth being inclined rearwardly from the tip of said teeth,
 a heel plate mounted for reciprocation in 5
 said guideways,
 the lower surface of said heel plate being spaced above the upper surface of said ski,
 a heel cover on said heel plate, 10
 a bell crank lever pivotally mounted adjacent to the edge of said heel plate,
 said bell crank lever having at the end of one arm a dog engageable with the teeth of said rack and at the end of its 15
 other arm a finger receiving portion, means resiliently urging the dog into engagement with the teeth of the rack,
 said dog having an inclined leading edge adapted to engage the inclined trailing 20
 edge of said rack teeth and a transverse trailing edge adapted to engage the transverse leading edge of said rack teeth,
 and an abutment extending upwardly from the 25
 heel plate directly behind the center line of the heel and along the centerline of the ski,
 said bell crank lever being so constructed and arranged that its finger engageable portion is movable approximately along the centerline of the ski and engages said abutment along said centerline whereby said lever may be depressed to release said dog from said rack and force may be applied to the heel plate along its centerline to move the plate in a longitudinal direction without binding and whereby force may be applied to the heel plate or heel cover in a direction toward the toe plate to permit ratchet 30
 adjustment of said heel plate.

2. A ski binder comprising
 a toe cover,
 and an adjustable heel plate assembly spaced behind the toe cover,
 said assembly comprising spaced guideways at each 45
 side of the ski,
 said guideways having inwardly directed opposed channels
 one of the guideways having teeth to provide 50
 a rack,
 the leading edge of said teeth being transverse to said rack and the trailing edge of said teeth being inclined,
 a heel plate mounted for reciprocation in 55
 said guideways,
 a bell crank lever pivotally mounted on
 said heel plate,
 said bell crank lever having at the end of one arm a dog engageable with the teeth of said rack and at the end of its other arm a finger receiving 60
 portion,
 means resiliently urging the dog into engagement with the teeth of the rack, 65

said dog having an inclined leading edge adapted to engage the inclined trailing edge of said rack teeth and a transverse trailing edge adapted to engage the transverse leading edge of said rack teeth,
 and an abutment extending upwardly from the heel plate directly behind the center line of the heel and along the centerline of the ski,
 said bell crank lever being so constructed and arranged that its finger engageable portion is movable approximately along the centerline of the ski and engages said abutment along said centerline whereby said lever may be depressed to release said dog from said rack and force may be applied to the heel plate along its centerline to move the plate in a longitudinal direction without binding and whereby force may be applied to the heel plate or heel cover in a direction toward the toe plate to permit ratchet adjustment of said heel plate.

3. An adjustable heel plate assembly comprising spaced guideways, a heel plate slidably received between the guideways, a lever pivotally mounted on said heel plate, said lever having tooth means engageable with said rack means and operating means spaced therefrom and positioned along the center line of the heel plate, means resiliently urging said tooth means into engagement with said rack means, and abutment means projecting from said heel plate along its center line and engageable by said operating means when the latter is depressed.

4. The invention of claim 3 in which said guideways support said heel plate above the surface on which the guideways are mounted.

5. The invention of claim 3 in which said rack means has inclined trailing edges on its teeth and said tooth means of said lever has an inclined leading edge whereby said heel plate may be moved forwardly without manually depressing said operating lever.

6. The invention of claim 3 in which said guideways have openings along their sides permitting the discharge of foreign matter.

7. A ski heel plate assembly comprising spaced slideways, a heel plate mounted for reciprocation in said slideways, one of said slideways having engageable means, a lever movably mounted on said heel plate and having engaging means for engaging said engageable means to restrict movement of said heel plate along said slideways, said lever having an operating portion positioned along the longitudinal centerline of said ski and operable by motion substantially along said centerline, and means urging said engaging means into engagement with said engageable means, whereby said engaging means may be released by operation of said portion and the application of force thereto along the centerline thereby obviating any tendency to bind of the heel plate in the slideways.
